GOTTHILF H. SCHWARZ, OF NEWARK, AND MAX VINTSCHGER, OF RIDGEWOOD, NEW JERSEY, ASSIGNEES TO THE POLE AND TUBE WORKS, INC., OF NEWARK, NEW JERSEY, A CORPORATION OF NEW JERSEY.

CONTAINER WITH REMOVABLE LOCKING COVER.

1,423,157.

Specification of Letters Patent. Patented July 18, 1922.

Application filed January 8, 1919. Serial No. 270,185.

To all whom it may concern:

Be it known that we, GOTTHILF H. SCHWARZ, of the city of Newark, county of Essex, State of New Jersey, and MAX VINTSCHGER, of Ridgewood, county of Bergen, State of New Jersey, citizens of the United States, have invented certain new and useful Improvements in a Container with Removable Locking Cover, of which the following is a specification.

The objects of our invention are to provide a container, preferably of metal, of can, barrel, or drum form, of simple, cheap and efficient construction, of long life, not deteriorated by the inclusion of oxidizing or corroding chemicals, such as strong acids, or alkalies; and also to provide such container, and other containers of like character, with a removable cover or closure, of a new and improved form, having a locking mechanism, also of a new, improved, simple, cheap and durable form of construction, of easy operation, by the use of which the cover may be instantly wholly removed from the container when the locking mechanism is thrown to the unlocking and releasing position; and as quickly returned to place and locked in the closed position, so as to render the container air and gas-tight, and other and further desirable capabilities and objects will be more fully hereinafter set forth in the description of our said container, its mode of operation and the method of forming the same.

Said invention is fully shown, described and claimed, in the following specification, of which the accompanying drawings form a part, wherein similar letters or numerals of reference designate similar parts wherever found throughout the several views; and in which:—

Figure 1, is a top plan view of one of our improved containers showing our improved form of cover thereon, in the closing and locked position; and

Fig. 2 is a like view thereof, showing the locking mechanism in the unlocked and releasing position ready for the cover to be lifted from the lower main body portion of the container.

Fig. 3 is a side view taken in central, vertical, longitudinal section on the line 3--3 of Fig. 1, looking upward in the direction

of the arrow, showing the cover in the hermetically closed and locked position shown in Fig. 1; and

Fig. 4 is a view thereof similar to Fig. 3, taken in central, vertical, longitudinal section on the line 4--4 of Fig. 3, the released cover being shown in a raised position, and about to be completely removed from the container.

Fig. 5 is a top plan view in detail, on an enlarged scale, of the main portion of our improved cover closing and locking mechanism in the fully locked position shown in Figs. 1 and 3; and

Fig. 6 is a like side view of the mechanism shown in Fig. 5, looking toward the left thereof, taken in vertical section on the line 6--6; and

Fig. 7 is a like end view of the portion of such locking mechanism showing the adjustable ring-throw regulating mechanism, taken in cross-section on the line 7--7 of Fig. 5, looking upward in the direction of the arrows; and

Fig. 8 is an enlarged end-view in detail of a portion of the container-top, annularly interiorly slotted chime-ring, cover, etc., in the locked position shown in Figs. 1 and 5, looking in the direction of the arrows 3 and 7.

Figs. 9, 10, 11 and 12, are views in detail, taken in vertical central cross section, of the bottom portion of our improved form of container with non-corrodible lining, showing the same in the various stages of construction; Fig. 11 showing the same in the finished or final form, and Fig. 12 being similar to Fig. 11, save that the non-corrodible lining is of one piece, instead of two, as in Figs. 9, 10 and 11.

Fig. 13, is a top-plan view on a slightly reduced scale of the cover-locking mechanism shown in Fig. 5, of a slightly modified form of construction, whereby greater range of adjustment in the expansion of the locking-ring is attained; and

Fig. 14, is a detail view in central vertical section, of the preferred form of bottom-joint of our new and improved container of our invention, which we usually use; such figure showing an unlined container, while the same form of our preferred bottom-joint is shown at the bottom of Fig.

4, as applied to a container having an inner non-oxidizable protecting lining upon the main shell, and also on the bottom-piece, covering the same and its outwardly extending flange, with the ends of such flange lining, and of the main shell lining extending thereover into the joint cavity of the securing ring.

Referring to the drawings:—

- 10 The reference letter A designates the main-body portion or shell of our improved container, which is formed of any suitable material that can be formed into any desired shape, size or contour, but which in the preferred form shown is of cylindrical form and usually of about the size and dimension of the ordinary shipping drum or barrel. In such case the main body, or cylinder shell, is formed in any suitable manner, of any suitable metal (usually sheet steel) of thickness suitable to withstand the rough usage to which containers are usually subjected during freighting, and such cylinder is closed at the bottom by an inwardly dished bottom-piece 25 B, the bottom annular peripheral flanged edge-portion 11 of which, when forced into place in the bottom portion of A fits tightly in an outwardly extended, enlarged bottom annular recess 12, formed by rolling or swaging or other suitable manner in the extreme bottom end portion of the shell-edge; as hereinafter more fully described.

In cases where the container is to be used for the reception of acidulous or alkaline materials, corrosive of steel or other metals, out of which the main body portion thereof is formed, an inner wall or lining, preferably and usually of lead, indicated by 14 is provided, and while this may be secured to the 30 main body portion A, and bottom B in any desired manner, such lining is usually inserted in the cylinder A, in the form of a cylinder of just such size as to be easily inserted therein, and then in any desired suitable means, swaged, rolled, or otherwise forced into close contact throughout its entire surface, with the interior of the main body or shell A, and further secured to the shell by electric spot or line welding, or in any other 45 suitable manner.

The bottom-ring C is first formed of any suitable metal, usually soft steel, in the form of a seamless integral ring having the upper inwardly extending annular securing main-body portion 15 merging gradually (as indicated at 16, Figs. 3, 4 and 9 to 12 inclusive) into the lower thinner bottom securing portion 13.

In carrying out the improved method and 50 process of forming containers herein described and claimed, slight changes and modifications in the various steps of such process may be made without departing from the scope of our invention, and we will first describe the same, as used in forming un-

lined containers, as the process is in its main essentials almost the same.

The main body portion A having been formed, and preferably but not necessarily swaged annularly outward at the bottom, to fit somewhat loosely into the annular lower portion 13 of the bottom-ring C, which is forced down over A from the top, into the position shown in Fig. 9, and the lower portion of A from the top 15 of the ring C to the bottom of A, rolled or swaged outward, in any desired manner, by any suitable tools or machinery, so as to contact lightly with the inner annular face of such ring, from the top 15 to the bottom line of the main body portion A.

The bottom B, having been in any desired manner, cast, forged, struck up, or spun into the dished form shown, so as to fit tightly into the outwardly and large bottom portion of the main body-portion A, is forced tightly into position therein, with the dished face outward (Figs. 9, 10, etc) and if in any manner loose, is more tightly fitted in place by the swaging or rolling outward of the 90 flange 20 thereof, in any suitable manner, and by any suitable means or mechanism, or fitted thereto in any other suitable way.

After this, by any suitable tools, means or mechanism, the lower, thinner annular securing portion 13 of the bottom-ring C is first swaged over the annular bottom edges of A and B, and then swaged, rolled or turned upward, inward and outward, so as to tightly enclose, cover and hold in place the lower depending end flanges of A and B, as clearly indicated in Figs. 1, 2, 11 and 12.

This operation is substantially similar, whether the container is provided with the lead or other non-corrosive lining 14 or not; and in some cases the entire lining 14, covering the interior of the main body portion A and the bottom B may be of a single piece dished inward at the bottom and having an annular bottom-fold 21 as indicated in Fig. 12, or the covering of the bottom-piece B may consist of a separate piece 14', entirely covering both the central disk, and the downwardly depending annular flange of such bottom-piece as clearly shown in Figs. 9, 10 and 11.

The lining 11, is turned outward, downward, and then backward so as to cover the annular beaded top-portion 22 (Fig. 8) of the main-body or shell A, and is further on the inside tightly swaged into the securing annular bead or groove 23, which forms the lower securing-member for the annular top chime-ring D, all as clearly indicated in Fig. 8.

Secured rigidly upon the top of the main body-portion A of the container is the annular, inwardly chamfered or channeled securing chime-ring D of substantially the shape 130

- shown, having the bottom wall-piece 25 and the upper wall-piece 26 downwardly and upwardly, inwardly flared, as shown in Figs. 1, 3, 4 and 8; which chime-ring is rigidly held 5 in position upon the top of the main body portion A of the container between the annular securing bead 23 and the top securing-bead 22 of A swaged down over the same, as clearly indicated in Fig. 8.
- 10 It is, of course, understood that by swaging or in any other manner, the bottom downwardly inclined annular securing ring wall-piece 25, is made to fit so tightly on the main body A, that the joint will be air-tight, 15 and if desired this joint in certain cases may be filled with solder, or a homogeneous joint made by electric welding.
- For closing the container at the top, while not limited thereto, we prefer to use the improved locking cover, closure or top E, of our new and improved form, comprising the main bottom portion 30, and having the annular outer-edged portion extending upward, outward and then slightly downward, 25 in order to form the gasket-groove 32, to receive the annular soft compressible gasket-ring 33, preferably of soft rubber or other suitable like material, such bottom in the lead or other like lined covers, to be used 30 with like containers, having the bottom face of the main bottom portion 30, provided with the covering 14, of the sheet-lead, etc. which covers the same completely as indicated in Figs. 3, 4 and 8, and is held in place 35 thereon by having the annular peripheral edge-portion 34, rolled into the gasket-ring groove 32, and rolled over the extreme edge at 34', (Fig. 8) the diameter of the cover being such that the same can be lifted easily 40 in and out of the chime-ring D, as clearly indicated in Fig. 4.
- Secured to the main bottom-portion 30 of the cover is the face-plate E', struck up into substantially the dished form shown, and secured to the bottom 30, by spot-welding, or 45 by rivets 35, which extend through 30, but not through the lead-sheet lining 14, and if desired, such lead sheet may also be more securely held to the bottom-piece by electric, 50 spot or other welding, at suitable points, (not shown) as may be all the like lining wherever used.
- Such securing face-plate E' is provided with the upwardly extending outer peripheral flange or wall 36, from which extends outward at substantially a right angle there-to the top-flange 37, beneath which is held in position on the cover the annular expansible cover-locking ring F, which is of the substantially truncated wedge-shaped form in cross-section shown in Fig. 8, the top downwardly and outwardly inclined securing face 38, of such ring being of the same length 55 from front to rear, as the coacting inclined lower face of the upper wall-piece 26 of the
- annular channelled chime-ring D, while the lower reversely inclined securing-face 39 of the locking-ring, extends much farther toward the center (to 40' of Fig. 8) so as to press the edge of the main-body of the cover 70 down upon the annular top bead 22 of the main-body portion A of the receptacle, so as to force the soft resilient gasket-ring 33 firmly down on such to-bead 22 so as to make an airtight joint between them, when forced 75 outward peripherally into the fully expanded position shown in Figs. 3 and 8.
- The annular flange or wall 36 of the cover face-plate E' is broken away at one side as shown at 41 (Figs. 1, 2 and 5) at the point 80 where the ring F is divided or cut across so as to permit the expansion and contraction thereof and through this opening or break 41, extends toward the cover center, the expanded and contracting mechanism G of 85 such cover-locking ring F, which is preferably but not necessarily of our improved variable and adjustable form shown, more fully hereinafter described, which comprises (Figs. 5 and 6) two lugs 42 and 43, each of 90 any suitable shape, size and construction, formed integral with or firmly secured to the inner face of the locking-ring F, one on either side of the slit lying between the two ends 40, thereof. As shown in Figs. 6 and 95 7, the lug 43, is a double one, being composed of the upper member 43, and the bottom member 43' (Fig. 6), and between them is pivotally secured by a pivot-pin, bolt or member 55, the short end of the bent hand-lever 47, which is pivotally connected at its elbow to a double centrally horizontally split toggle member or piece 45, by a pivot-bolt 46, while the other end 45 is in like manner pivotally connected with the ring-lug 42 100 105 beyond the split between the two ends 40, of the lock-ring by the pivot-bolt 44, this securing together at the split the two ends of the ring F, in such manner that when the handle or actuating long end of the bent lever 47 110 115 is thrown to the extreme left (Figs. 1 and 5) such ring F will be thrown into the extreme expanded, and cover locking position shown, for the reason that the pivot-pin or bolt 55, securing the toggle-member or piece 45 to the elbow of the bent-hand actuated lever 47, will have been forced peripherally outward so far that a straight line (the dotted line in Fig. 5) cutting the centers of the pivot-pins or bolts 44 and 46, will pass inward of the 120 center of the pivot-pin or bolt 46, so that the resiliency of the expanded ring F, tending to keep the levers in such position, the entire mechanism will be firmly locked therein against any accidental throwing to the central or rightward unlocking position, indicated in Fig. 2. And in order that the hand lever 47 may be used as a handle to lift out and off the cover, when thrown to such releasing position, without danger of being 125 130

bent, the extreme end thereof vibrates back and forth in the arc of a circle underneath an arcuate guard-piece 49, struck up out of the securing face-plate E so as to be still secured thereto at the peripheral face and ends, and free therefrom at the inner face of the arcuate guard-piece 49 so formed.

It has been discovered by actual use, that in some cases, by reason of a partial rotation 10 of the securing and locking-ring F, especially when being thrown into the fully expanded and cover-locking position, that cutting, scoring and grinding and wearing action upon the inner face of the chime-ring D, 15 is liable to be caused by contact therewith, often sufficient to give rise after some time to such imperfect closure of the joint between the cover and main-body portion A as to allow of atmospheric or other leakage 20 thereat; and to reduce this to a minimum, and to provide easy and quick means for curing any such trouble that might possibly arise, we provide a stop pin 50 secured by riveting, or spot-welding, etc. at its bottom 25 end to the main bottom portion 30 of the cover E, and extending upwards therefrom in the slot of the ring F, or at least within the bases of the lugs 42 and 43 thereof, in such manner as to limit the rotative movement 30 of the ring F, to the very slightest, by abutment against such pin of one of the lugs, or the adjacent ends of the ring.

As broadly described in the last preceding paragraph but one, the lock-ring expanding, 35 locking and releasing mechanism may be non-adjustable like mechanism shown, described and claimed in our co-pending application Serial No. 223,447, filed March 19, 1918, entitled Containers, etc., upon which 40 Letters Patent No. 1,314,708, were granted Sept. 2, 1919, but in this, our improved form shown in the drawings, with but slight but important changes in the construction we have rendered such ring-expanding and contracting mechanism easily and quickly adjustable, by which the amount of the expansion of the ring, when the hand lever is thrown to the extreme cover closing and locking position, may be varied within all 45 possible and desirable limits, whether for the purpose of overcoming wear or distortion, fitting in the first instance, or changing the cover from one can to another. As shown in the drawings, in our preferred form of such 50 adjustable ring expanding and cover-locking mechanism, the ring-lug 42 is a single lug, and the toggle-member secured is usually a double or two-piece link, composed of the upper piece or bar 45, and a lower like 55 piece or bar 45' secured at one end to the ring-lug 42 by the pivot-pin, 44, and at the other by a pivot-pin or bolt 46 to the elbow of the bent lever 47. The other ring-lug is a double one, composed of an upper elongated member 43, and a lower member 43',

each formed integral with or secured to the ring F, at that end, and with just space enough between them to permit of the reception and free vibratory movement therein of the short end of the bent hand-lever 47.

As clearly shown in Figs. 6 and 7, formed in and through the upper elongated ring-locked member 43 (Fig. 7) is a cylindrical journal-box or orifice 53, and in the shorter bottom-like member 43' is formed a like 75 journal-box or orifice 54, of smaller diameter than 53, and with its axes coincident with that of 53; and revolvably supported in 53 and 54, by the upper journal 53', and the lower-journal 54' is the adjustable eccentric throw-member 55, formed integral with 80 53' and 54', and also with the end-throw journal 56, all of which journals and journal-boxes are cylindrical, in cross-section; but the throw-member 55 has its axis on the 85 line d—d, while the axes of 56, 53' and 54' are all coincident and on the line c—c. And it will be seen that by this peculiar and particular arrangement, by rotating such throw-member 55, upon the coincident axes, of 56, 90 53' and 54' that the amount of movement exerted by the hand-lever 47 may be varied a distance equal to the eccentricity of the axis of 55 lying on the line d—d from that of the line c—c.

Rigidly secured upon the end throw-journal 56 by means of a set-screw (not shown), or in any other desired manner, is the throw adjusting-sector 60, having adjacent to its periphery the arcuate line of lock-perforations 61, 61' and 61''; and formed in and through the top of the upper elongated lug member 43 of the expandible-ring F, so as to register successively with the perforations 61 to 61'', as the sector 60 is swung or 100 vibrated over the same, is a threaded lock-screw perforation or orifice 58, to receive the threaded end of the lock-screw 62 when passed through any one of the sector perforations 61 to 61'' inclusive, into the same, 105 according to the extension of the ring-throw or expansion desired, whereby such sector, and the adjusting and locking mechanisms will be firmly locked against any accidental displacement.

As is clearly shown in Figs. 5, 6 and 7, (and incidentally also in Figs. 1 and 2) by this peculiar construction and arrangement, it will be seen that as the eccentric throw-member 55 lies in the orifice or journal 55', 120 formed in and through the short end of the lock-lever 47, so as to permit free vibration of such lever thereon, and is held in such position solely by the lock-screw 62, that when such screw is screwed fully out of 58, 125 such member 55, and sector 60, being lifted bodily upward and out of the lugs 43 and 43', the throw-lever 47 will be disconnected, and the locking-mechanism disconnected from the expandible ring.

As shown in such figures, it will also be seen that when the sector 60 is in the medial position, with the lock-screw 62, in the central lock perforation 61', (as shown in Fig. 5) the throw-member 55, will also be in medial position, and that the short, bent end of the handle or throw-lever 47, will also be in like medial central position relative to its pivotal connection with the lock-ring by way of the lugs 43 and 43'.

It will also be seen that when the sector 60 is thrown to the extreme top of Fig. 5, and the lock-screw passed down through the last lock-perforation 61 on the lower side of Fig. 5, into the lock orifice 58, that when 55 is in such position, that the lock-lever 47 will then press against the rear edge of the member 55 on the side nearest to the axial line *d-d* thereof, whereby the hand-lever 47, will, when thrown to the ring expanding and locking position shown in Fig. 1, and Fig. 5, exert a thrust of less length upon the ring equivalent to one-half of its eccentricity; and that, per contra, when it is thrown to the left to the opposite extremity, and the lock-screw 62 is passed down into and through the upper lock sector perforation 61'', that such thrust upon the lock-ring will be increased in like manner from that exerted at the medial position, also one-half of the eccentricity of the throw-member 55. From which it will be seen that in this vibration of the sector, from end to end, the throw and opening movement of the expanding securing-ring or lock-ring may be widely but minutely varied.

And while as shown in Figs. 1, 2, 5 and 6, the sector has a throw and a periphery of only about one-sixth of a circle, being practically a sextant, and that being so limited, the throw of the member 55, does not give the full adjustment of its whole eccentricity, for many purposes such throw is sufficient; but in the modified form of construction, shown in Fig. 13, we have shown a sector-plate of half-circle form, in which the full eccentricity of the throw-member 55 may be used for such purposes of adjustment, in the positions assumed by it when at the point of the exertion of the least throwing movement of the lever 47 and the consequent least expansive movement of the lock-ring possible to be made, or vice versa.

It will be seen that by this particular construction of the locking mechanism the expanding and contracting movement of the securing lock-ring may be varied within micrometric dimensions from the extreme eccentricity of the throw-member 55 to the distances between any two of the perforations 61, etc. of the sector; but we do not intend to limit ourselves to this particular form of adjusting mechanism, and consider that any other suitable means or mechanism which will bring about a like micro-metric

adjustment of the amount of throw, of the lock-ring will be within the scope of our invention.

In like manner, we do not intend to limit ourselves to the exact construction of any other part of our invention herein disclosed, nor do we exact chronological sequence of the various steps of our improved method of forming the container-bodies and securing the bottoms to the shell thereof herein described.

As an illustration the bottom ring C instead of being made with a depending flange 13, as shown in Fig. 9, may be initially cast, rolled, or otherwise formed, into the substantially L shaped form in cross-section, shown as the second step down in Fig. 10, the bottom B then forced into the as yet unenlarged bottom end of the shell A, the bottom-ring C forced on the shell A, and the shell and depending flange of the bottom-piece roll or otherwise forced back tightly into the space between the shoulder 16, and the foot of the L 13', of Fig. 10, into the position shown in Figs. 11 and 12, either before, or simultaneously with the turning-inward and forcing outward of such flange-portion 13' and other modifications may be made, all without departing from the scope of said invention our new and improved can, container or receptacle herein disclosed, described and claimed, which would suggest themselves to skilled mechanics after reading the specification the essential principle of which broadly stated, in so far as the formation of a receptacle bottom is concerned, consists in producing a can or container comprising a main-body or shell and a bottom-piece formed separate therefrom forced into an annular peripheral enlargement at the bottom of such shell, and a ring of one piece fitting upon the main-body portion of the shell above the enlargement, and turned up over and around the bottom and shell inward, and then forced outward so as to enclose the depending annular edges of the bottom-piece and shell in an annular chamber of the bottom-ring, as so completely formed, by the bending into proper shape of such one-piece annular bottom-ring.

We claim:—

1. A container comprising a peripheral main-body portion or annular shell having an annular outwardly extending enlarged end portion; and end-piece for the shell having a peripheral outwardly extending annular-flange fitting tightly in the end of the shell; and an annular end-ring exteriorly tightly concentrically superposed upon the end of the shell and swaged inward, upward and then annularly outward tightly upon the outwardly extending annular-flange of the end-piece and the outwardly concentrically mounted

end portion of the shell, so as to enclose such shell end-portion and end-piece flange in a ring-formed annular-chamber lying wholly outward of the inner annular peripheral surface of the upper portion of the 5 end-ring concentrically fitting upon the exterior of the main-body portion of the shell.

2. A container comprising a main body 10 portion or shell of substantially annular form; a bottom-piece for the shell having a peripheral outwardly and downwardly extending annular-flange fitting tightly in the end of the shell; and an integrally formed 15 one-piece annular bottom-ring fitting tightly on the end of the shell, tightly enclosing in an annular-chamber of such bottom-ring, (formed by forcing the lower outward annular portion of such bottom-ring inward, 20 upward, and outward,) the peripheral outwardly and downwardly extending flange of the bottom-piece and the bottom portion of the shell concentric with such flange; the shell, and bottom piece and its flange, being 25 provided with a protecting lining, that portion of such lining at the outer surface of the flange of the bottom-piece, and that covering the lower end of the inner surface of the peripheral wall of the shell, being in 30 contact one with another, and tightly compressed in the annular joint-chamber of the bottom ring.

3. The combination with a container, body or shell, having a filling and delivery opening, of a removable cover for closing the 35 opening; locking mechanism for locking the cover and the opening, and for forcing the cover inward, into place in the opening so as to seal the same; a vibrating lock-lever 40 carried by the cover for actuating the locking-mechanism; and an arcuate guard-piece secured to the cover, extending outward therefrom, beneath which the free moving end of the lock-lever vibrates.

4. A container comprising a main-body or shell, a chime-ring secured at the receiving and delivery end of the shell; a seal-seat at the top of the delivery opening located 45 within the chime-ring; a removable cover adapted to be inserted in the opening within the chime-ring; a sealing ring or gasket carried by the cover adapted to co-act with the seal-seat; an expansible lock-ring carried by the cover, adapted, when thrown to the 50 expanded position, to coact with the chime-ring in such manner as to force the cover inward, so as to seal the opening by contact of the sealing gasket and seat; mechanism for retracting and expanding the ring; a 55 hand-lever for actuating such mechanism; and mechanism for regulating the extent of the throw given to the expanding lock-ring with a given movement of the lever.

5. The combination, with a container, 60 body or shell, having a filling and delivery

opening, of a removable cover for closing the opening; a chime-ring secured at the receiving and delivery end of the shell; a seal-seat at the top of the delivery opening located within the chime-ring; a sealing- 70 ring or gasket carried by the cover adapted to co-act with the seal-seat; an expansible lock-ring carried by the cover; a face-plate having an annular outwardly extending flange which covers against outward displacement the expanding lock-ring, secured to the main body portion of the cover; mechanism for retracting and expanding the ring; a hand-lever for actuating such mechanism; and mechanism for regulating the 80 extent of the throw given to the expanding lock-ring with a given movement of the lever; the free vibrating end of the lever vibrating underneath an arcuate guard-piece formed integral with and struck up 85 outwardly from the cover-plate.

6. In a device of the class described, a substantially cylindrical main-body or shell; an end closing or bottom-piece for the shell having an outwardly extending annular peripheral flange closing the end of the shell with the flange concentrically located within the shell; an annular ring outwardly concentrically mounted upon the shell and bottom-piece flange and enclosing the flange and shell end adjacent in an annular chamber closed at the outer end by the turning inward, upward and then annularly outward of the outer portion of the ring; a filling and delivery opening located at the top end of the 100 shell; a removable cover for closing the opening; a chime-ring surrounding the opening; a seal-seat at the top of the delivery opening located within the chime-ring; a sealing ring or gasket carried by the cover adapted 105 to coact with the seal-seat; an expansible lock-ring carried by the cover; a face-plate having an annular outwardly extending flange which covers the expanding lock-ring, and secures the same against outward displacement secured to the cover; and hand actuated mechanism for contracting and expanding the lock-ring.

7. In a device of the class described, the combination with a container body or shell 115 having a suitable receiving and delivering orifice, of a removable cover having an expansible split-locking-ring carried at the peripheral edge of the same, of a ring expanding and contracting mechanism comprising 120 a plurality of levers one of them adapted to be hand actuated connecting the two ends of the ring at the split; the connection to one end of the ring being made by and through an adjusting-member connected 125 pivotally with one of the levers so that the same will vibrate thereon; and connected with one end of the split ring so as to be rotated in the connection on an axis eccentric to the axis of the portion connecting the 130

- same with the lever; and means for so rotating the adjusting-member in the connection, and locking the same in various positions so as to vary the throw of the ring upon a given 5 length of throw of the actuating-lever.
8. In a device of the class described, the combination with a container body or shell having a suitable receiving and delivering orifice, of a removable cover having an expansible split locking-ring peripherally carried by the cover, of substantially wedge-shape with the point toward the periphery, in cross-section, of a ring contracting and expanding hand actuated mechanism 10

10. In a device of the class described, the combination with a container body or shell having a suitable receiving and delivering orifice, of a chime-ring, provided on the inner face with an annular peripheral recess having an inwardly upwardly flaring top-wall secured to the shell and surrounding the filling and delivery orifice; a seal-seat at the top of the shell within the chime-ring; a removable cover with a seal-seat adapted to coact with the shell seal-seat to form perfect closure thereof; an expansible split locking-ring of substantially outwardly pointed wedge shape in cross-section, having an upper downwardly inclined surface adapted to coact with the under inclined surface of the upper wall of the recess when expanded into the same so as to force the cover down upon the shell seal-seat, carried by the cover, such locking-ring having a lower upwardly and outwardly inclined wedge-face, extending inward so far that when the ring is fully expanded the inclined wedge-face will be in close contact with the cover edge above the cover-seal-seat; and mechanism for contracting and expanding the locking-ring. 45 50 55 60 65 70
11. A device comprising the characteristics set forth and enumerated in claim 2, wherein the annular joint-holding and retaining annular chamber is located wholly 75 outward of the inner surface of the upper portion of the retaining and securing-ring and of the outer surface of the main abutting portion of the shell.
